(57) **CLAIM**

The ornamental design for a shoe, as shown and described.

DESCRIPTION

FIG. 1 is a top, right, and front perspective view of an ornamental design for a shoe;

FIG. 2 is a left side elevational view of the shoe of FIG. 1; FIG. 3 is a right side elevational view of the shoe of FIG. 1; and,

FIG. 4 is a bottom plan view of the shoe of FIG. 1.

The dash-dash-dash broken lines are included for the purpose of illustrating portions of the shoe that form no part of the claimed design. A transition in tonal contrast shown along the front cushion is claimed.
